HAND BUCKLE MACHINE

Nobe J. Keith, Brenham, Tex.

Application May 8, 1934, Serial No. 724,629

Renewed September 11, 1935

3 Claims. (Cl. 153—40)

This invention has reference to a machine for applying a buckle to a band or strap of metal, and particularly for applying buckles to bands used in conjunction with cotton compresses.

5 The invention also consists in the provision of an improved method of folding one end of a band in a manner to positively secure the buckle thereto, as well as the provision of an efficient hand machine for working the end of the band.

10 The invention together with its objects and advantages will be best understood from a study of the following description taken in connection with the accompanying drawings wherein:

Figure 1 is an elevational view of the machine.

15 Figure 2 is a top plan view thereof.

Figure 3 is a perspective view showing the first step in applying the buckle to the band.

20 Figure 4 is a similar view illustrating the next to the last step in applying the buckle and after the folding of the band by the machine has been completed.

Figure 5 is a perspective view illustrating the final step in the application of the buckle to the band.

25 Figure 6 is a perspective view of an ejector sleeve.

Figure 7 is a perspective view of the folding head and associated shaft.

30 Referring to the drawings by reference numerals it will be seen that the machine comprises a base or platform 5 having rising from one edge thereof a support 6 which in the present instance extends for substantially the full length of the base 5. Provided on the upper edge of the support 6 intermediate its ends is a bearing 7 in which is journaled a shaft 8 equipped on one end with a hand crank 9.

35 On the end thereof opposite to the crank 9 the shaft 8 is provided with a head 10 which is provided with a series of fingers 11, in the present instance preferably three fingers arranged in staggered relation as shown.

40 Slidably engaged with the shank portion of the head 10 is a sleeve 27 provided adjacent one end with a collar 28 adapted to abut the adjacent end of the bearing 7 for limiting inward movement of the sleeve 27 relative to the head. At its forward end the sleeve 27 has removably secured therein through the medium of a pin 29 an ejector element 30 that is adapted to operate in a slot 31 provided therefor in the head 10.

45 For reciprocating the sleeve 27 there is provided a lever 18 that is pivoted at 19 to a lug projecting from the support 6, and on the under side thereof the lever 18 is equipped with

spaced depending lugs 31' that are disposed at opposite sides of the flange 28 for engagement therewith to project or retract the sleeve upon swinging movement of the lever 18 in the proper direction.

5 A curved carrier member 13 is pivoted to the base 5 as at 14 and is provided at its free end with a freely journaled roller 15. The carrier is normally urged to rotate in a clockwise direction (Figure 1) through the medium of a coil 10 spring 16 that is anchored at one end to the base 5 as at 17 and is secured at its opposite end to the carrier 13 as shown in Figure 1. It will thus be seen that under action of the spring 16 the roller 15 will be held in constant contact with 15 the band 12 during rotation of the head 10 in the manifolding operation.

20 The carrier 13 on one side thereof is provided with a lug 21 with which is engageable a lug 20 carried by the lever 18 upon movement of the 20 lever 18 forwardly to project the sleeve 27. It will thus be seen that incidental to a projection of the sleeve 27 the carrier 13 will be caused to swing in a counter-clockwise direction away from the edge 10 thus permitting of the folded portion 25 of the band 12 being forced out of engagement with the fingers 11 of the head 10. This latter operation is performed obviously, by upon projection of the sleeve 27, and engagement of the pin 30 with the folded portion of the strap 30 12 in a manner to force said portion in the direction of the length of the fingers to become disengaged therefrom.

35 In using the machine the buckle 13a is first passed on to one end of the band 12 as suggested in Figure 3. The end of the band is then passed through the fingers 11. Next the crank 9 is rotated to effect a manifold bending of the band 12, the band first folding to provide the fold 22, then the fold 23 and finally the fold 24. When 40 this folding operation is completed the end of the band may be folded as shown in Figure 4. Upon completion of this operation the lever 18 is swung forwardly to project the sleeve 27 and thereby engage the member 30 carried by the 45 sleeve with the folded portion of the band to disengage said portion from the head 10 in a manner hereinbefore explained.

50 When the folding operation has been completed and the band disengaged from the head 10 50 buckle 13a is then slid forwardly into position between the bend 25 connecting the folds 22 and 23 and the bend 26 connecting the fold 24 with the strap proper.

55 When the buckle 13a has been moved to the 55

position just stated a second attendant with a mallet or the like completes the folding, and when the folding operation is completed the folds, as shown in Figure 5 will be parallel to one another and with the strap 12 with a portion of the frame of the buckle positively secured in place and in a manner not to easily work loose.

Having thus described my invention, what I claim as new is:

- 10 1. A hand machine for applying buckles to metallic bands comprising a rotatably supported shaft, a head on the shaft provided with a series of staggeredly arranged fingers adapted to have an end of a band threaded therethrough so that 15 upon rotation of the head the manifolding of the band may be accomplished, and means associated with the head for disengaging the folded portion of the band from said head, said means including a sleeve slidable on the shaft longitudinally thereof, and an ejector member arranged 20 within one end of the sleeve and operating between certain fingers on the head in a manner to engage an edge portion of the band upon projection of the sleeve forwardly with respect to the head, and means for projecting and retracting 25 said sleeve including a collar on the sleeve, a pivotally mounted lever, and spaced lugs on the lever engaging the collar at opposite sides thereof for transmitting movement of the lever to the 30 sleeve.
2. A folding machine of the class described comprising a base, a support rising therefrom, a shaft rotatably mounted on the support, a folding head on one end of the shaft, and provided 35 with a slot, an ejector sleeve slidably mounted on the shaft, an ejector member provided in one end

of the sleeve and arranged to operate within the slot, said sleeve being also provided with a collar, a lever pivoted at one end to the support and provided intermediate its ends with lugs engaging opposite sides of the collar for transmitting movement of the lever to the sleeve, a carrier member pivoted on the base laterally of the shaft, a roller carried by the carrier member for engaging the article to be folded during rotation of the head, and spring means engaged with the carrier for normally urging the roller into operative position relative to said head.

3. A folding machine of the class described comprising a base, a support rising therefrom, a shaft rotatably mounted on the support, a folding head on one end of the shaft, and provided with a slot, an ejector sleeve slidably mounted on the shaft, an ejector member provided in one end of the sleeve and arranged to operate within the slot, said sleeve being also provided with a 20 collar, a lever pivoted at one end to the support and provided intermediate its ends with lugs engaging opposite sides of the collar for transmitting movement of the lever to the sleeve, a carrier member pivoted on the base laterally of the 25 shaft, a roller carried by the carrier member for engaging the article to be folded during rotation of the head, and spring means engaged with the carrier for normally urging the roller into operative position relative to said head, said carrier 30 being provided with a lug, and said lever being provided with a lug for engaging the lug on the carrier to swing the latter in a direction away from the head upon movement of the lever to project said sleeve.

NOBE J. KEITH.
